UNITED STATES PATENT OFFICE.

LEWIS W. SCUTT, OF CLEVELAND, OHIO.

UMBRELLA-MARKER.

1,369,846.

Specification of Letters Patent.

Patented Mar. 1, 1921.

Application filed November 29, 1918. Serial No. 264,521.

To all whom it may concern:

Be it known that I, LEWIS W. SCUTT, a citizen of the United States, residing at Cleveland, in the county of Cuyahoga and State of Ohio, have invented a certain new and useful Improvement in Umbrella-Markers, of which the following is a full, clear, and exact description, reference being had to the accompanying drawings.

10 This invention relates to a device for marking or checking umbrellas and the like; and the main object is to provide a durable and inexpensive device of this character which may be quickly and conveniently attached to an umbrella, taking the place of the common forms of checks that are attached by means of leather straps. This prevailing method of checking umbrellas has several disadvantages. The looping of the 15 strap about the umbrella consumes considerable time; the strap often becomes tangled occasioning further delay; the loop of the strap tears out easily especially after the leather deteriorates from frequent wetting; 20 and the check suspended from the strap becomes infolded within the cover of the umbrella and concealed from view, making it inconvenient to identify the umbrella by check number. These difficulties are over- 25 come by the use of my improved marker.

Further objects of my invention are to provide a device of the aforesaid character involving a loop through which the umbrella may be projected in such a way that 30 the cover of the umbrella will be compressed into small scope and held against undue flaring; to provide a device of this nature involving a confining yoke for retaining the ends of the ribs closely about the handle; to 35 connect the loop and yoke by a resilient stem which is placed under tension when the device is applied to an umbrella, thereby to securely hold the device in place and the 40 umbrella in the condition above described; to incorporate in the device a hook for supporting it from a rack or the like and in such manner as to hold the umbrella against swinging in any direction; to include a 45 marker or tag which is disposed in plain view when the device is applied to an umbrella; and, preferably, to provide the de-

vice with means for removably attaching to it a check bearing an identification mark corresponding to that on the tag of the marker, so that the check may be easily and 55 quickly removed by the checker and presented to the depositor of the umbrella.

These several objects are attained in the embodiment of my invention illustrated in the accompanying drawing wherein Figure 60 1 is a perspective view of the marker ready for use and carrying the detachable check; Fig. 2 is a similar view of the upper end of the device with the detachable check removed; Fig. 3 is a perspective view showing 65 the marker applied to an umbrella and the umbrella supported by the marker upon a rack; Fig. 4 is an enlarged sectional detail through the supporting rail of the rack and showing the manner in which the hook of 70 the marker co-operates with the rail; and Figs. 5 and 6 are diagrams, the former indicating the marker in its relaxed condition removed from an umbrella, and the latter showing the device under tension as when 75 applied to an umbrella.

The device is preferably formed of a single piece of resilient wire that is formed at one end into a loop 1, connected by a stem 2 to a suspension hook 3. Extending laterally from the hook 3 is a retaining yoke 4, the same terminating in a compressible loop 5 adapted to be forcibly projected through a slot 6 of a check 7, the loop 5 being so constructed as to yield as the check is forced 80 over its enlarged end after which it expands slightly to engage a notch 8 of the loop within the end of the slot. The extreme end of the wire whereof the loop 5 is formed reposes within an offset 9 in the adjacent 85 branch of the yoke 4 so that the end of the wire cannot in any way interfere with adjacent parts of the umbrella.

A marker or tag 10 is attached to parallel portions of the wire where they form the 90 top of the suspension hook 3 as by having its ends bent over and under such parallel portions, the tag, and the check 7 associated with the particular device, bearing corresponding designations.

In the use of the device, the check 7 is removed and presented to the party deposit-

ing the umbrella; the umbrella is inserted through the loop 1 and the stem 2 is sprung laterally sufficiently to engage the yoke 4 about the ends of the umbrella ribs, and, 5 when released, the tendency of the stem 2 to straighten places the entire device sufficiently under tension to hold the parts snugly together. The hook 3, having a broad bearing surface on the top of the supporting rail 11 of the rack 12 prevents the umbrella swinging sidewise; and the fact that it snugly embraces the top edge of the rail, engaging the front and rear surfaces thereof, as shown in Fig. 4, prevents the 10 umbrella from swinging at right angles to the rail.

Thus it will be seen that my invention provides a neat, inexpensive and very durable device which may be conveniently and 20 quickly applied to such articles as umbrellas, for the purpose of marking them or suspending them from suitable supports. Attention is also called to the fact that the marker is so designed as to permit its use 25 with standard types of checks.

Having thus described my invention, what I claim is:—

1. An umbrella marker comprising a loop for engagement about the cover of the umbrella, a yoke for confining the ends of the ribs in proximity to the handle, a stem connecting the loop and yoke, and an identifying 30 device incorporated in the assembly.

2. An umbrella marker comprising a loop 35 for engagement about the cover of the umbrella, a yoke for confining the ends of the ribs in proximity to the handle, a stem connecting the loop and yoke, an identifying device incorporated in the assembly, and 40 means for detachably connecting a corresponding identifying device to the assembly.

3. In a device of the character set forth, the combination of a loop, a stem to which 45 the loop is connected, a laterally extending yoke spaced from the loop and connected to the stem, and a suspension hook incorporated in the assembly.

4. In a device of the character set forth, the combination of a loop, a stem to one 50 end of which the loop is connected, a laterally extending yoke connected to the opposite end of the stem, and a suspension hook at the junction of the yoke with the stem.

5. In a device of the character set forth, 55 the combination of a loop, a stem to one end of which the loop is connected, a laterally extending yoke connected to the opposite end of the same, a suspension hook at the junction of the yoke with the stem, and 60 identifying means incorporated in the device adjacent the suspension hook.

6. A device of the character set forth comprising a loop, a stem to one end of which the loop is connected, a yoke connected to

the opposite end of the stem, a marker incorporated in the device, the device having an expanding portion over which an identification check is adapted to be removably engaged. 65

7. A device of the character set forth 70 formed of resilient material and comprising a stem, a loop at one end thereof and adapted to be engaged about one portion of an article, a yoke at the opposite end of the stem and adapted, when the stem is sprung laterally, to be engaged about a remote portion 75 of the article, and an identifying device incorporated in the assembly.

8. A device of the character set forth 80 formed of resilient material and comprising a stem, a loop at one end thereof and adapted to be engaged about one portion of an article, a yoke at the opposite end of the stem and adapted, when the stem is sprung laterally, to be engaged about a remote portion 85 of the article, and a supporting hook incorporated in said assembly.

9. A device of the character set forth comprising a single piece of resilient wire formed at one end to constitute a loop and at 90 the other end to constitute a yoke in a plane at substantially right angles to the normal plane of the yoke, an intermediate portion of the wire being formed into a suspension hook. 95

10. An umbrella marker comprising a single piece of resilient wire formed at one end to constitute a loop, and at the other end to constitute a yoke in a plane at substantially right angles to the normal plane of the yoke, 100 and an identification device applied to the wire.

11. A device of the character set forth, constructed of resilient wire terminating at one end in a loop, a remote portion of the wire extending laterally at right angles then downwardly and upwardly in a plane substantially parallel to the body portion of the wire and then in a direction parallel to the aforesaid right angle portion, the wire therebeyond extending downwardly in substantially the plane of the body portion and laterally into the form of a yoke. 110

12. A device of the character set forth 115 constructed of resilient wire terminating at one end in a loop, a remote portion of the wire extending laterally at right angles then downwardly and upwardly in a plane substantially parallel to the body portion of the wire and then in a direction parallel to the aforesaid right angle portion, the wire therebeyond extending downwardly in substantially the plane of the body portion and laterally into the form of a yoke, the end portion of the wire turning back over itself 120 and toward the adjacent branch of the yoke to constitute a loop over which a slotted check is adapted to be removably engaged, 125

one branch of said loop having a retaining notch for the check, and a metal strap having its ends engaged about the parallel portions of the wire, the strap and check bearing corresponding marks of identification.

13. A device of the character set forth comprising a resilient portion formed to en-

circle the cover of an umbrella and hold the same compact, and identification means included in said device.

In testimony whereof, I hereunto affix my signature.

LEWIS W. SCUTT.
